US00D879078S

(12) **United States Design Patent** (10) **Patent No.:** **US D879,078 S**
(45) **Date of Patent:** **** Mar. 24, 2020**

(54) **MOBILE DEVICE SIGNAL BOOSTER**

(71) Applicant: **Wilson Electronics, LLC**, St. George, UT (US)

(72) Inventors: **Joshua Boggs**, Aledo, TX (US); **Scot Herbst**, Santa Cruz, CA (US)

(73) Assignee: **Wilson Electronics, LLC**, St. George, UT (US)

(**) Term: **15 Years**

(21) Appl. No.: **29/625,667**

(22) Filed: **Nov. 10, 2017**

(51) **LOC (12) Cl.** **14-03**

(52) **U.S. Cl.**

USPC **D14/230**; D14/240

(58) **Field of Classification Search**

USPC D14/230-238, 138, 172, 188, 203.1, D14/203.3, 203.6, 204, 216, 221, 238.1, D14/240, 242, 299, 314, 343, 356, 358, D14/496, 509; D13/107, 108; D12/42, D12/43

CPC H01Q 1/007; H01Q 1/084; H01Q 1/12; H01Q 1/22; H01Q 1/38; H01Q 1/42; H01Q 7/00; H01Q 9/40; H01Q 9/285; H01Q 9/065; H01Q 9/44; H01Q 9/265; H01Q 19/10; H01Q 19/106; H01Q 19/12; H01Q 19/13; H01Q 19/15; H01Q 19/30; H01Q 21/28; H01Q 21/06; H01Q 21/062; H01Q 21/293; H01Q 23/00; H01Q 1/32; H01Q 1/3275; G05D 1/02; G05D 1/0234

(57) **CLAIM**

The ornamental design for a mobile device signal booster, as shown and described.

DESCRIPTION

FIG. 1 is a front perspective view of the presently claimed design.

FIG. 2 is a front view of the presently claimed design.

FIG. 3 is a rear view of the presently claimed design.

FIG. 4 is a side view of the presently claimed design.

FIG. 5 is an opposite side view of the presently claimed design.

FIG. 6 is a top view of the presently claimed design; and, FIG. 7 is a bottom view of the presently claimed design. The broken lines depict portions of the article that form no part of the claimed design.

1 Claim, 7 Drawing Sheets
